UNITED STATES PATENT OFFICE.

JEAN B. OLINGER, OF MILWAUKEE, WISCONSIN.

GEOGRAPHICAL INDEX FOR CLOCKS.

1,034,496.

Specification of Letters Patent. Patented Aug. 6, 1912.

Application filed November 18, 1910. Serial No. 593,086.

To all whom it may concern:

Be it known that I, JEAN B. OLINGER, of Milwaukee, in the county of Milwaukee and State of Wisconsin, have invented a 5 Geographical Index for Clocks, of which the following is a specification.

In my former Patent No. 935,806 issued October 5, 1909, I described a means of showing upon an ordinary clock-dial the 10 hours for various principal points or countries all around the earth; said means consisting in fixing to the hour-hand arbor of a clock, or otherwise mounting so that it will rotate with the hour-hand and concentrically with the clock dial, a disk having 15 a ring divided into 24 radial sectors alternately black and white which represent the different cities, countries or points of the earth's surface. I have found by 20 experience that said dial as disclosed in my aforesaid patent presented certain disadvantages which it is the object of the present invention to avoid by means of certain improvements which will hereinafter 25 appear.

Standing clocks are frequently wound through an aperture in the dial thereof, and when said dial is covered by an annular disk such as that described and claimed in 30 my former patent it has the disadvantage of covering the winding-hole so that a special winding-device is necessary in order to wind the clock; and this makes it inapplicable or difficultly applicable to ordinary 35 clocks. Another disadvantage which said annular disk presents lies in the fact that the aforesaid sector-shaped divisions of the disk so run together at their edges that it is not easy to tell at a glance which dark 40 segments belong with which light ones, and to find any desired segment, and the hour indicated by it, requires some search, because the edges of the segment run together.

In my present improved index I provide 45 a dial which is in the form of a star having 12 rays, each of which carries a hand or index at its extremity, thereby guiding the eye directly to the proper point of the clock-dial; and each of said 12 rays is 50 divided longitudinally into dark and light portions corresponding to opposite meridians of the globe, or antipodal countries or places; thus grouping the various places together in twelve sets, which are much more 55 readily observable to the eye. At the same time I gain the advantage of enabling said

dial to be used with ordinary clocks, since the winding-hole or holes will be uncovered whenever they are opposite the spaces between the rays, at which time a key may be applied. Moreover in my present construction the meaning and method of reading the dial is obvious to almost any one at a glance and requires no instructions or set of directions, which in public clocks is a very 65 important element, as the public will not stop to study out a device which requires time and pains. In my present form of index I may moreover dispense with the hour-hand entirely, by coloring one of the 70 12 points, being the point corresponding to the place where the user is located, a special color or tint, or otherwise distinguishing it from the rest, whereby it takes the place of an hour-hand. 75

My invention comprises, more precisely stated, the construction which will be hereinafter more particularly described and is set forth in my claims, reference being had to the accompanying drawing, Figure 1 of 80 which shows a face-view of the index, and Figs. 2 and 3 respectively, side and end views of an attachment therefor.

The index has a central aperture *s* of the diameter of the hour-hand arbor or sleeve 85 and adapted to slide over the same and to be fixed thereto in any desired manner, as for example that shown in my aforesaid patent. Immediately concentric with the aperture *s* is preferably placed a cartographic polar 90 projection *a* of the earth as shown, divided by meridians, which will in this case be radial, at 15 degrees interval, and these may be properly designated in the numbered circle *b*. This map and circle are, however, not 95 essential to the invention. The outer periphery is formed by the twelve equidistant star-points *f*, which are longitudinally divided into light and dark divisions as shown, and terminated by the hand or pointer *M*. 100 On the dark and light spaces of each star-point are placed the names of places at opposite meridians of the earth, and these may be marked with their corresponding longitudes. For example, the uppermost star-point of the drawing is designated "London" in the light space and "Fiji Islands" 105 in the dark space; the former being numbered 0, which is the meridian of London, and the latter 180, which is the meridian of Fiji Islands. On the pointers *M* are placed 110 the respective time numbers *r*, said numbers

indicating the difference of time between any two hands; for example, the Milwaukee hand being designated 19 and the Klondike hand 22, the difference in time between these places is 22 minus 19 or three hours. Each hand contains two numbers, one on a light ground, the other on a dark one, referring to the respective sectors of the star-point on which it is located.

10 This index can be placed on any clock or watch and it will be apparent at a glance what the meaning of the several star-points is; especially will this be true of one of the points, for example the Milwaukee-Calcutta point as shown in the drawings, be tinted or colored as is indicated by the shaded lines. So tinted or colored, said star-point would serve the purpose of an hour-hand for a person located on or near 20 the meridian of Milwaukee or that of Calcutta.

If the index is carried on the watch of a person who is traveling, or upon a clock which is being moved from one point to another, instead of tinting or coloring one of the points, a tinted translucent overlay or strip C may be used, as for example a piece of red celluloid or isinglass, mounted concentrically with the hour arbor by means 30 of the hole c and having tabs d on its edges adapted to engage temporarily over the edges of any one of the star-points; said strip may be freely moved from one star-point to the other by simply raising the end 35 and disengaging the tabs d from one star-point and placing the strip over another one.

While I have hereinabove shown the most improved form of my invention, I wish it understood that not all of the features are 40 essential thereto or necessarily made in the exact form shown, but various changes and modifications in the constructions as herein shown may be made without departing from the spirit of my invention, and I wish it understood therefore that the latter is not 45 otherwise limited than by the scope of my claims.

Having thus described my invention, what I claim as new and desire to secure by 50 Letters Patent is:

1. A geographical-index adapted to be attached to the hour-arbor of a clock or watch and having twelve independent equidistant rays, each ray being marked with 55 one or more places or parts of the earth's surface within an angle of 30 degrees longitude thereupon or its antipode, and a shiftable bar of translucent material pivoted and freely movable concentrically with the hour-arbor and adapted to be shifted so as to 60 overlie any one of said rays at the option of the holder and thereby distinguish it from the others; said bar having means for

temporarily holding it in the position in which it is placed.

2. A geographical-index adapted to be attached to the hour-arbor of a clock or watch and having twelve independent equidistant rays, each ray corresponding to one or more places or parts of the earth's surface of corresponding longitude; in combination with a shiftable bar of translucent, tinted, springy material, having the same outline as a ray, and adapted to lie flat upon any of the rays; said shiftable bar being pivoted and freely movable concentrically with the hour-arbor, and adapted to be shifted so as to overlie any one of said rays at the option of the holder and thereby distinguish it from the others; and said bar having means near the end thereof for engaging it with the ray which it overlies.

3. A geographical-index adapted to be attached to the hour-arbor of a clock or watch and having twelve independent, equidistant rays, each ray corresponding to one or more places or parts of the earth's surface of corresponding longitude; in combination with a shiftable bar of translucent, tinted, springy material, having the same outline as a ray, and adapted to lie flat upon any of the rays; said shiftable bar being pivoted and freely movable concentrically with the hour-arbor, and adapted to be shifted so as to overlie any one of said rays at the option of the holder and thereby distinguish it from the others; and said bar having at or near its ends a pair of down-turned tabs, which when the bar lies normally flat upon the surface of the ray engage with the edges of said ray, and prevent lateral shifting, thereby enabling said bar to be radially shifted from one ray to another by simply raising the tip thereof.

4. A geographical-index adapted to be attached to the hour-arbor of a clock or watch and having twelve independent, equidistant rays, each ray bisected longitudinally by a line of division and having on one side of said line the names of one or more places or 100 geographical features located within an angle of 30 degrees longitude corresponding to the relative positions of the respective rays and on the other side of said line the names of other places or geographical features antipodal to the first-named places or features; each ray being further truncated transversely near its end, and carrying upon its end a special pointer in the form of a hand.

In witness whereof I have hereunto set my hand in the presence of two witnesses.

JEAN B. OLINGER.
